UNITED STATES PATENT OFFICE

RAY A. BROWN, OF ROCKFORD, ILLINOIS

STEREOTYPE-CASTING MACHINE

Application filed November 16, 1928. Serial No. 319,776.

This invention relates to stereotype casting machines of the kind especially adapted for use by small newspaper publishers and in jobbing and other printing shops for casting stereotype plates from matrices furnished by newspaper, advertising, and other service agencies. The principles of my invention are, however, not limited to stereotype casting machines of this particular size or for this limited use, but are generally applicable in the casting of stereotype plates.

One of the primary objects of my invention is to provide a generally improved and simplified stereotype casting machine of the character described which will be easy to operate and practical for the purposes intended.

The machine is also so designed that it may be produced at a comparatively low cost and yet be sturdy in construction and durable under the working conditions of a machine of this kind.

In carrying out my invention I use a casting box and a melting pot constructed and mounted in a novel manner so as to make the operation of the machine both easy and convenient. The casting box, consisting preferably of an upper and a lower platen, is mounted in a low frame so as to swing to and from a horizontally disposed work-receiving position and a vertically disposed metal-receiving or casting position. While the casting box may be mounted in a number of ways, it has been found convenient to pivot it on the frame at a point intermediate its ends whereby it may be rotated with but little effort. The melting pot, preferably of the bottom pouring type, is mounted upon the frame through parallel links and is normally carried at a point above one end of the frame over a heater, but may be swung to a point above the other end of the frame for the purpose of pouring the cast. The melting pot is automatically kept in an upright position at all times making operation safe from splashing metal.

Other objects and attendant advantages will be appreciated by those skilled in the art as the invention becomes better under-

stood by reference to the following description and the accompanying drawings.

Figure 1 is a side elevation of the machine, the dotted lines showing the casting box open in the work-receiving position and set to produce type high castings;

Fig. 2, is a side elevation of the machine showing the casting box and melting pot in the metal pouring position and set to produce type high castings; and

Fig. 3, is a front view of the machine showing the melting pot in the heating position and the casting box in the work-receiving position with the platens clamped together ready to be shifted into the pouring position.

The casting box may be of any preferred construction. In the present instance it is composed of an upper and a lower platen designated generally by 5 and 6. The lower platen is rotatably connected by means of bolts 8 so that it may be swung between an open and a closed position and permit the ready placing of the matrices and gauges. The upper platen is held in the open position by means of the slotted latch 10 which is pivoted on the upper platen at 11 and slides over a guide pin 12 in the lower platen. A series of clamps 13 are provided for clamping the plates together during the casting operation. The casting box is constructed for making either "type high" or "thin plate" castings. For making the type high castings the platens will be connected as shown with the bolts at 8, while for making thin plate casting the connection will be made with the bolts at 9, to accommodate the casting box to the thin plate gauges.

The casting box may be supported by any suitable means whereby it may be moved between a horizontally disposed work-receiving position and a vertically disposed metal-receiving or casting position. In this instance I employ two standards generally designated by 14 and 15 having bearings 16 into which trunnions 17 on the lower platen are journaled. Suitable tie rods 18 and 19 are provided to hold the standards in rigid relation.

The melting pot designated generally by

20, resting in the cradle 21, which serves to hold the melting pot in position and acts as a shield to guide the hot gases along the walls of the pot, is supported and guided by the 5 bars 22 and 23, 22 serving as a supporting rod and 23 as a guide rod to keep the melting pot upright at all times. The supporting rods are pivotally mounted on the frame at 24 and on the cradle at 26. The guide rods are 10 pivotally connected to the frame at 25 and pivotally connected to the arm 27 which is fixed to the cradle. The length of the arc through which the melting pot may swing is defined by the stops 35 and 36, stop 35 15 being so placed as to hold the melting pot in the pouring position over the vertically disposed casting box and stop 36 being placed to hold the melting pot in its normal position over the burner and clear of the casting 20 box. The flow of metal from the pot is controlled from the lever 28 mounted on the melting pot and attached to a plunger in the spout 32 through the link 30. The weight 31 is placed on the end of the lever to cause it 25 to return to the closed position when released.

Any suitable means may be used for heating the melting pot such as gas, oil, and electric heaters. I have shown an oil burner 30 generally designated by 34, resting upon a bracket or shelf 33 attached to one end of the frame. It thus rests directly under the melting pot while the latter is in its heating position supplying the heat necessary for 35 melting and maintaining the metal in the proper condition for use.

The operation of my improved casting machine is safe, convenient and easy. Fig. 1 shows the normal starting position with the 40 casting box open and the melting pot being heated over the burner. In practice it is necessary for the operator to first cast a blank or slug to heat up the casting box. The slug is permitted to cool and is returned to the melting pot. The operator should then arrange the matrices and gauges upon the lower 45 platen in the usual manner, lower the upper platen, clamping it securely in place, and then shift the casting box from its horizontally disposed position to a vertically disposed position for casting, where it will be firmly held by the latch 37. The melting pot should then be swung from its heating position over the burner to its pouring position 50 over the vertically disposed casting box. A stop on the frame is provided to prevent the melting pot from going beyond the proper position for pouring. The operator may then pour the cast by depressing the lever 60 and permitting the molten metal to fill the casting box. Reversal of the operations will bring the machine back into its original position for removal of the stereotype plate.

It is evident that the operation of my improved machine is simple, that but little spe-

cial training is required of the operator, that due to the bottom pouring pot molten metal is not handled directly with the attending dangers from burns, and that the machine is free from many of the structural defects 70 of prior machines.

It is believed that the foregoing conveys a clear understanding of the objects, and while I have illustrated but a single embodiment, it should be understood that changes 75 might be made in the construction and arrangement without departing from the spirit and scope of the invention as expressed in the appended claims.

I claim:

1. A stereotype casting machine consisting of a supporting frame, a casting box, a bottom pouring melting pot, supporting rods for pivotally supporting said melting pot on said frame, one end being pivotally attached to said frame the other end pivotally attached to said melting pot permitting it to move in an arc above the supporting frame, means for holding the melting pot upright while being swung from one position to another, and means for heating the melting pot. 80

2. A stereotype casting machine consisting of supporting frame, a casting box pivotally mounted on said frame, a heating means, a bottom pouring melting pot, supporting rods for pivotally supporting said melting pot on said frame, one end being pivotally attached to the frame, the other end pivotally attached to the melting pot permitting it to move in an arc above the frame, and a second pivotal connection between the melting pot and the supporting frame for the purpose of maintaining the melting pot in an upright position while the latter is swung from one position to another and whereby the spout will be brought into exact pouring relation with the casting box when the latter is in the pouring position. 95

3. A stereotype casting machine consisting of a supporting frame, a casting box including an upper and a lower platen mounted to move between a horizontal and a vertical position, a bottom pouring melting pot, supporting rods for pivotally supporting said melting pot on the frame one end of which is pivotally attached to the frame in a lower horizontal plane than the casting box, the other end being pivotally attached to the melting pot permitting it to move in an arc above the frame, means for holding the melting pot upright while being swung from one position to another, and heating means mounted at one end of the frame for heating the melting pot when in the heating position. 100

4. A stereotype casting machine consisting of a melting pot, a frame above which the melting pot is adapted to swing from a metal-pouring position at one end to a heating position at the other end, supports for the 110

melting pot extending from a point near the base of the frame to the melting pot, a casting box pivotally mounted on one end of the frame, and means for heating the melting pot mounted on the frame opposite the casting box.

5 In witness of the foregoing I affix my signature.
